UNITED STATES PATENT OFFICE.

EDWIN T. GREENFIELD, OF BROOKLYN, N. Y., ASSIGNOR OF ONE-HALF TO
THE HOLMES BURGLAR ALARM TELEGRAPH COMPANY, OF NEW YORK.

TELEPHONE-EXCHANGE SYSTEM.

SPECIFICATION forming part of Letters Patent No. 256,432, dated April 11, 1882.

Application filed April 23, 1880. (No model.)

To all whom it may concern:

Be it known that I, EDWIN T. GREENFIELD, of the city of Brooklyn and State of New York, have invented a new and useful Improvement 5 in Telephone-Exchange Systems and Apparatus therefor, of which the following is a specification.

The present invention relates to the construction and arrangement of apparatus to be used in a central telephone-office, whereby exchanges between the various customers and offices connected with such central office can be effected quickly, easily, and economically; and the principal features of the invention are 15 the use of a switch-board provided with a local ground, the combination, with a switch-board, of multiple receiving and transmitting instruments, and a series of automatic drops or equivalent signal devices arranged in combination with the switch-board and the "listening-off" apparatus, all as more fully herein-after set forth and claimed.

In the accompanying drawings, which fully illustrate this invention, Figure 1 is a general 25 perspective view of the combined apparatus, S B indicating the switch-board, R the multiple receiver, T the multiple transmitter, and L O the listening-off mechanism, consisting of a series of automatic drops, a key-board, and an 30 ordinary telephone. The switch-board, for convenience of illustration, is shown of smaller size relatively to the other parts than would occur in actual use. For the same reason the transmitter, the receiver, and the listening-off 35 apparatus are shown in closer proximity to the switch-board and to each other than would be found convenient for practical purposes.

Fig. 2 is a rear view of the switch-board, showing the switches and the wires of the local ground, as well as the general wiring of 40 the board.

Figs. 3 and 4 are side elevations of one of the switches, Fig. 4 showing the position of the parts with the switch-plug P in place, and 45 Fig. 3 the parts with the plug removed.

Fig. 5 is a sectional view of the compound receiver, showing two of the magnets, Fig. 6 being a plan of the same receiver with the cap and diaphragm removed.

50 Fig. 7 is a perspective of the compound transmitter, the hinged door or cover which

carries the mouth-piece, the diaphragm and the connected parts being thrown open and a portion of the case being broken away, so as to show the interior of the instrument.

55

Fig. 8 is a longitudinal section through the key-board and one of the drops, showing also the connection of these parts with the switch-board and with the earth.

These drawings represent the improved apparatus as arranged for use in connection with the service-lines of eight subscribers or customers; but the system may be applied to any desired number of lines.

Referring to the several divisions of the apparatus more in detail, the receiving-instrument R, to which all the service-lines pass after leaving the switch-board, is a multiple instrument constructed on the general plan illustrated in Figs. 5 and 6, in which there is 65 shown a single diaphragm combined with a multiplicity of magnets and coils, the number of coils being one-half the number of lines in the system. To effect this the lines are connected with the instrument in pairs, each pair 70 of conductors being joined to a common coil. So far as concerns this multiple receiver, the present invention relates to the coupling of two conductors upon a single coil or spool, the use generally of a multiplicity of magnets or 75 coils in a single receiving-instrument being the special subject of another application for patent, heretofore filed by me, and therefore not claimed herein. As fully explained in such prior application, the use in a single receiver 80 of a number of separate magnets or coils, or equivalent devices, enables a single "listener-on" to keep watch over and receive orders from a large number of lines.

The transmitter T is also a multiple or compound instrument, containing a single mouth-piece and diaphragm and one-half as many induction-coils as there are customers in the system, the secondary wires of the several coils uniting the service-wires in pairs in like manner as they are united in pairs by the coils of the receiver. The mouth-piece and diaphragm, and the parts more immediately connected therewith, may be of any ordinary construction, and therefore are not here shown in 95 detail. So far, again, as concerns this multiple transmitter, the present invention relates 100

only to the coupling of two conductors upon a single induction-coil, the use generally in a transmitter of a multiplicity of induction coils or equivalent devices under the control of a common diaphragm being the special subject of another application, filed by me contemporaneously herewith, and therefore not claimed herein.

The switch-board S B consists in part of an upright frame provided with the usual metallic union-strips, A B C D, arranged horizontally upon its face, and with vertical metallic strips upon its rear, the latter being so arranged relatively to holes passing through the former and through the board that metallic plugs inserted in such holes will bear against the elastic flanges of the vertical strips and thus enable the operator at pleasure to establish electrical connection between any one of the front and any one of the rear set of strips.

E is the main wire of a local ground-connection, leaving the switch-board at any convenient point, as F, and grounded at G. From this main wire E branch wires are run to each of the switches S' S² S³, &c. The switches are each composed of three projecting lips or flanges, l l' l'', of elastic sheet-brass or other equivalent material, so arranged that the insertion of a metallic pin or plug of the proper size through any of the lower series of holes in the switch-board will press the lip l away from the lip l', as shown in Fig. 4, while the withdrawal of the plug will permit such lip to spring back into contact with l', as shown in Fig. 3. Moreover, the lip l is so related to the lip l'' that after the switch-plug is inserted between them, as above indicated, it bears against them both, and thus establishes an electrical connection between them, such connection in turn being broken when the plug is withdrawn.

The customers' lines are represented by 1, 2, 3, 4, 5, 6, 7, and 8, and the wiring of the switch-board is as follows: From the several binding-posts through which these lines enter the switch-board the wires pass to the corresponding vertical strips, 1^a 2^a 3^a, &c., and thence to the upper member, l'', of the switches. From the lower member, l, of the switches the wires 1^b 2^b 3^b, &c., run to a second set of binding-posts, and after leaving these last named posts the wires are looped together in pairs—1^c with 2^c, 3^c with 4^c, &c.—each loop being passed through the transmitter and the receiver.

From the above explanation of the construction of the apparatus its operation will be apparent. When the switch-plugs are all in place in the switches S' S², &c., each customer's line is in connection, through the switch-board, with both the receiver and the transmitter, and through these with the ground of that line to which it is itself coupled. It follows that any customer can at any time call the central station by simply throwing his telephone into circuit with his special line in the usual way, and, also, that when he has thus put himself in communication with the central

station he can hear any message that may be spoken into the multiple transmitter, whether intended specially for him or for any other person. If, now, any customer, as No. 3, desires to communicate with any other, as No. 6, he calls the central office and gives his order, as "3 on 6." The switchman receiving the order from the listener-on disconnects No. 3 from No. 4 and No. 6 from No. 5 by removing the plugs from the switches S³ and S⁶ of lines 3 and 6, and inserts these plugs directly above in any one of the horizontal union-strips, as B, which may happen at the time to be unoccupied. In this way the lines of No. 3 and No. 6 are connected, each taking the ground of the other, and No. 6 being rung up, everything is in condition for the transaction of business between them. Although by this arrangement No. 4 has been cut off from the ground of No. 3, and in like manner No. 5 from the ground of No. 6, yet the closing of the lips l l' of the switches of lines 3 and 6 consequent upon this withdrawal of the switch-plugs has thrown lines 4 and 5 onto the local ground E, and as these lines still pass through the transmitter and the receiver communications can take place freely over these lines to and from the central office.

The great advantage of thus coupling up the lines in pairs, which seems to be rendered practicable only by the use of the local ground, is that the multiple instruments—the receiver and transmitter—can be made more compact than would otherwise be possible, and thus a larger number of lines be brought under the control of a single operator or set of operators.

The mode of "ringing up" the customers when two are to be connected for purposes of communication is as follows: After the two are plugged in on one of the horizontal union-strips, as above explained, such strip is tapped several times with the key K. This key forms one pole of a local battery, and each time it touches the strip a current dividing at the point of contact passes over each of the two customers' wires and rings a bell, or otherwise sounds an alarm, in the office of each customer. This is notice to the calling customer that he is connected with the person desired, and is notice to the called customer that he is connected with some one who desires communication with him, and thereupon the called customer throws his telephone into the line and hails such other person. Manifestly, also, instead of using a battery with which to excite the lines for signaling the customers, an induced current might be similarly utilized by means of a key, K.

The listening-off apparatus is constructed and operates as follows: Each of the horizontal union-strips A B C D of the switch-board is electrically connected with a corresponding key, A B, &c., upon the key-board by wires arranged in any suitable manner. The contact-points of these several keys, when the keys are depressed, touch a metal strip, H,

which is connected through the binding-post I with the earth, and at any convenient point in this earth-connection there is placed an ordinary transmitting and receiving instrument, 5 J. From the wires that connect the union-strips of the switch-board with the several keys of the key-board branch wires diverge and pass to corresponding drops, A' B', &c., which are placed convenient to the key-board, and from 10 these drops other wires lead down to the earth-connection of the key-board. In practice there should be as many drops as there are union-strips on the switch-board; but in the drawings, Fig. 1, only two drops are shown, one of 15 which, D', has its cover up, indicating that the corresponding strip is not in use, while the other, B', has its cover down, displaying the letter B, which indicates to the listener-off that two customers are plugged onto the corresponding strip.

L is an electro-magnet having an armature, M, mounted upon or forming one end of a pivoted lever, the other end of which is notched to hold up the cover of the drop, 20 which is readily accomplished so long as the armature is out of contact with the magnet. The moment a current passes through the coil and magnetizes the soft-iron core the armature is drawn down, and this elevates the 25 notched end of the armature-lever and releases the cover, which immediately falls and displays a number or a letter like that which distinguishes the corresponding union-strip of the switch-board. Each branch wire which 30 leads off from the connections between the switch-board and the key-board connects with one end of the coil of the electro-magnet of the corresponding drop, the other end of this coil being connected with the metallic frame of the 35 drop, and thus when the cover of the drop is raised an electrical connection is secured, through such cover and the spring n, against which the cover bears when raised, with the wire that leads from the drop to the earth-connection of the key-board, such wire being insulated from the frame of the drop; but when 40 the cover of the drop falls the contact between it and the spring n is broken and the electrical connection through the drop is destroyed. 45 From this construction it follows that whenever two service-lines are plugged onto one of the union-strips of the switch-board, and a local current is thrown onto such strip for signaling the two customers, as above described, 50 a portion of such current will also flow to the drop, and by exciting the electro-magnet will throw down the cover of the drop, and thus indicate to the listener-off that the corresponding strip is in use. Thereafter it becomes the 55 duty of the listener-off to keep watch of the lines connected with the union-strip indicated by the drop and ascertain when communication between these lines has ceased, whereupon he is to notify the switchman, who will 60 at once disconnect the two lines and restore each to its normal connection with the switch-

board by removing the plugs from the union-strip and replacing them in the lower series of holes.

While the above will be found the most convenient and reliable mode of operating the drops, plainly some other current than that above indicated might be utilized for this purpose. All that the listener-off is required to do in order to learn whether communications 70 are passing between the lines which are shown by the drop to be jacked together upon any one of the union-strips is to depress the key corresponding to such drop, which at once puts the telephone of the listener-off into a 75 branch circuit diverging from the main circuit between the two customers who are electrically connected. By simply listening in his telephone the listener-off can ascertain whether communications between the customers have 80 ceased. Thus one listener-off can readily keep watch over a large number of lines.

It will be seen that the above system in its practical working is one of great simplicity and efficiency. Three persons at the central 90 office can readily take charge of a large number of lines and transact the business with accuracy and without confusion. All the words that it is necessary to have spoken at the central office are the repeating to the switchman 95 by the listener-on of the order which he hears in his receiver—as “3 on 6”—and the order from the listener-off to the switchman to disconnect any parties who have ceased talking, such order, for instance, being, in brief, “disconnect B,” which signifies “disconnect the parties who are jacked onto union-strip B.” Thus all confusion at the central office, with the consequent danger of mistakes, is avoided. There is practically no chance of any customers who 100 have ceased communication being cut off from the central office, as sometimes occurs under some of the existing systems; and three attendants in the central office can serve efficiently at least six times as many customers as would 105 be practicable under one of the most generally adopted systems in use at the present time.

I do not in this application claim the above-described mode of ringing up and signaling customers by the use of a local battery, having withdrawn my claim therefor, as originally filed, for the purpose of making the subject thereof the basis of an application for a separate patent.

What is claimed as new is—

1. The combination, in a telephone-exchange system, of a plurality of service-lines with multiple receiving and transmitting instruments at the central station, each line being connected through the instrument with another line of the system, whereby each line normally or in a state of rest is grounded through such other line.

2. The combination, in a telephone-exchange system, of a plurality of service-lines arranged in groups, so that in their normal condition or a state of rest each has as its ground the ground

- of some one of the other lines, a switch-board, and a local ground at the central station, arranged substantially as set forth, whereby any line cut off from its normal ground may take the local ground of the central station.
3. The combination, in a telephone-exchange apparatus, of a switch-board, a multiple receiver, and a plurality of service-lines leading through the switch-board to such receiver.
- 10 4. The combination, in a telephone-exchange apparatus, of a switch-board, a multiple transmitter, and a plurality of service-lines leading from such transmitter to the switch-board, and thence to the customers.
- 15 5. The combination, in a telephone-exchange system, of two service-lines and a single coil in each of the instruments (the receiver and the transmitter) of the central station, each

line being connected through such coils with the other line, whereby each line normally or in a ²⁰ state of rest is grounded through the other line.

6. In combination with the key-board of the listening-off apparatus, a series of automatic drops arranged and connected to be operated at the time of placing the customers in communication, substantially as described.

7. In combination with the union-strips of the switch-board of a central telephone-station, a series of automatic drops arranged to be operated by the same current with which the ²⁵ switchman signals the customers, substantially as set forth.
